TYPOGRAPHICAL COMPOSING MACHINE

Luther E. Morrison, New York, N. Y., assignor to
 Mergenthaler Linotype Company, a corpora-
 tion of New York

Application October 20, 1937, Serial No. 170,007

40 Claims. (Cl. 199—19)

This invention relates to typographical composing machines, such as Linotype machines of the general organization represented in U. S. Letters Patent to O. Mergenthaler, No. 436,532, and has for its principal object the adaptation of machines of this kind for printing in languages employing many symbols or characters in their printed expression.

A typographical composing machine of the class stated comprises, among other parts, a keyboard and a matrix font representative of the type characters to appear in print. By the depression of the keys of the keyboard, the matrices, through the action of intermediate parts, are released in the proper order from their storage magazine and assembled in line for the casting therefrom of type bars or printing slugs. It is with these parts of a composing machine that the present invention is particularly concerned.

The number of keys which the keyboard of a typographical composing machine can comprise must be held within certain limits in order that the machine may be operated with the necessary facility, speed and accuracy. The keyboard of the regular commercial machine known and widely used in this country, comprises but ninety (90) different keys, and it has been found in practice that keys to that number will answer the ordinary requirements for printing in the many languages in which the machines are now used. For example, a keyboard, whose keys are marked with the characters used in printing in the English language, will customarily have ninety (90) keys as just stated, such as a key for each lower-case letter of the alphabet, a key for each upper-case letter of the alphabet, a key for each small-cap letter of the alphabet, and a key for each of the various other symbols used in printing, such as numerals, punctuation marks, etcetera. In short, there will be a separate key for each separate character of the matrix font employed in the magazine, each key being connected directly to the corresponding magazine channel.

There are some languages which employ very many more symbols and characters than ninety (90). The Hebrew language, for instance, involves the use of at least three hundred (300) essential characters or symbols for its printed expression with the fullest detail and complete accuracy. And it may be stated here that this invention has in particular contemplation the provision of a composing machine for printing in the Hebrew language, the following description applying specifically to that language.

The Hebrew language is composed of twenty-

seven (27) consonants (twenty-two pure or intermediate consonants and five final consonants) and twelve (12) vowels (nine general and three special). Words may be written without the use of vowels, but in such case there is a loss of accuracy because a word written without vowels may be susceptible of several meanings. For example, the three Hebrew consonants corresponding to the English letters "d", "b", and "r" form, when combined, a Hebrew word which can properly be translated in nine different ways, as dobor, dobar, dever, diber, dibeyr, dabeyer, dauer, dover and d'var. Only by the use of vowels, or the reading of the text, can a differentiation in meaning be made.

The setting of Hebrew vowels is difficult because of the fact that they do not follow the consonant as in the case of Latin alphabets. Thus, the Hebrew vowel may occupy one or more of three positions in relation to its consonant, i. e., may be placed under the letter, within the letter, or above the letter, or in any two or all of these positions. In those cases where the vowel unit is placed within the consonant, the characters are termed "dagheesh", but so far as the present invention is concerned, these dagheesh characters will be treated as consonants, since they, notwithstanding the middle vowel which they carry, also carry other vowels placed either above or below the consonant.

The method in common use to-day for the setting of Hebrew characters with properly positioned vowels is by hand composition. In this method, the consonants are set first and the vowels are then set above or below the consonants. This method is slow, laborious, difficult to handle, and costly and, moreover, because of the very minute size of the vowel symbols, involves a severe and damaging strain on the eyes.

In an effort to adapt the commercial composing machines to Hebrew composition, it has been proposed to cast a slug with a line of consonants and then cast another and separate slug with a line of vowels, the two slugs then to be placed side by side to make up a composite type line with the vowels below the consonants, no attempt being made to place the vowels above the consonants. This method was found to be altogether unsatisfactory, as the vowel units could not be placed in their required positions with relation to the consonants with the necessary exactness, not to mention other serious mechanical and objectionable difficulties.

In another attempt to adapt the commercial composing machines to Hebrew composition, it

has been proposed to employ a matrix font consisting of a group of meaningless letter elements which, when composed in line in group-assembly of two or three, form the character of a complete Hebrew consonant without a vowel, with any required vowel, or with vowels above, in the center, or below the consonant letter, or in any combination of these positions (see, for example, the Bloom and Friedman Patent No. 2,006,435). By this method, according to the Bloom and Friedman patent, it is possible by the use of sixty-three (63) special letter and vowel elements to make up as many complete Hebrew characters as may be required for printing. While this method permits the composition of a large number of characters by the use of a limited number of finger keys in the keyboard, the difficulty is that the index characters carried by the finger keys must necessarily represent only those portions of complete characters which are borne by the matrices released by the corresponding keys. Thus, dealing with a Hebrew character which requires the composition in line of three different letter elements, the index characters borne by the three corresponding keys represent each only a third of the complete character, and in most cases these index characters are meaningless and almost unrecognizable. As a result, composition can only be carried on by an operator who has made a careful and painstaking study of the different arbitrary characters and knows how they are used in building up complete characters. Even then composition is difficult because the system contemplates the use of many of the meaningless character elements in building up various complete characters. In addition, the work of composition is slow and tedious, because naturally each complete character composed in line requires the actuation of two or three keys to select for the group-assembly the particular elements required to make up that character. Other difficulties and objections exist but enough has been said to indicate that there is room for improvement.

In still another effort to adapt the commercial composing machine to Hebrew composition, it has been proposed to employ a matrix font in which the individual matrices of the font will carry complete Hebrew characters; whether they represent consonants with or consonants without vowels. This means, of course, that the number of different characters in the matrix font will greatly exceed the number of finger keys in the keyboard, but to reduce the total number of keys required, this same method provides for placing two different complete characters on each matrix of the font, with the result that the number of finger keys in the keyboard will be just one-half of the total number of characters comprised in the matrix font. Even so, the number of finger keys exceeds the usual number of ninety, and each finger key is required to carry two index characters, one representing, say, a consonant without a vowel and the other a consonant with a vowel, or consonants with different vowels. Such a method of composition is fully disclosed in the Goldblatt Patent No. 1,807,523. In this patent, as will be found, the keyboard comprises 126 different keys, each bearing in effect two different index characters, thus making it possible to control the release of 252 different complete characters, some of which, however, are not Hebrew characters, but are miscellaneous characters required for Hebrew composition. Because of the great number of keys and of the great number

of index characters which they bear, Goldblatt divides the finger keys into four different groups, and the matrix font into four corresponding groups, in order to facilitate the selection of the different characters. The grouping of the finger keys is such that the index characters in the respective groups are alike in respect to the consonant parts of the complete characters, the groups being distinguished from each other in respect to the vowels associated with the consonant parts of the complete characters. As to the two index characters carried by each key, one of these in the first group represents a consonant only and the other a vowel only, which means, that whenever a key of this group is actuated, it will release a matrix bearing a consonant character without a vowel or the same consonant with the vowel borne by the finger key, depending upon the level at which the two-letter matrix controlled by the finger key is composed. As to the index characters in the other groups, one represents a consonant with a vowel and the other a vowel only (a different vowel), so that whenever a finger key in any of the three other groups is actuated, it will release a matrix bearing the same consonant with one vowel or the other vowel, depending upon the level at which the two-letter matrix released by that key is composed.

In carrying on composition under the Goldblatt system, it is apparent that difficulty will be encountered in selecting the different characters, it being necessary first to find the group in which the desired character is located and then the finger key in the group which will release that character, but before the finger key can be actuated, the operator is also compelled to determine the level at which the matrix to be released is to be composed in line, involving, as is well understood in the art, the operation of the so-called duplex assembler rail in the assembler elevator.

The present invention, like that disclosed in the Goldblatt patent, contemplates a matrix font in which the individual matrices will carry complete Hebrew characters with or without vowels (thus allowing the characters to be of strictly orthodox form) but provides a keyboard with the minimum number of finger keys to control the selection of all of the complete characters. Whereas the Goldblatt keyboard comprises 126 finger keys, each bearing two different index characters, the keyboard of this invention comprises but 60 finger keys, each bearing only a single index character. Of the sixty finger keys, twenty-seven (the principal ones with which this invention is concerned) bear index characters representing consonants only, and the remaining thirty-three bear miscellaneous characters, some special Hebrew characters and other numerals, punctuation marks, etcetera, used in Hebrew composition. So far as the twenty-seven principal keys are concerned, they are normally connected to a group of magazine channels containing matrices bearing corresponding consonant characters without vowels, but provision is made for connecting the keys to other groups of magazine channels containing matrices bearing the same consonant characters with vowels. In the present instance, there are seven other such groups, these groups being differentiated from each other by the vowels carried by the consonant characters. Such connection of the finger keys to the seven different vowel-groups of matrices is controlled by the employment of as many different shift keys, each bearing as an index character

one of the seven vowels. In this way, by employing twenty-seven different matrix releasing finger keys and seven different shift keys, it is possible to provide for the selection and release of two hundred sixteen (216) different Hebrew characters. Thus, whenever it is desired to compose in line a matrix bearing a consonant without a vowel, the operator need only actuate the matrix releasing finger key bearing the corresponding index character. On the other hand, whenever it is desired to select a matrix bearing a consonant with any one of the seven vowels, it is only necessary first to actuate the shift key bearing the index character for the corresponding vowel and then to actuate the finger key bearing the index character representing the consonant. As above explained, the actuation of the shift key connects the keyboard to the corresponding vowel group of magazine channels, and the actuation of the finger key of course controls the release of the corresponding matrix of that group. Here it may be explained that each shift key is held depressed until the finger key has been actuated (as in the case of the ordinary typewriter), but when the shift key is released, the keyboard will be re-connected automatically to the group of magazine channels containing matrices bearing consonants without vowels.

It will thus be seen that, according to the invention, the matrix font is divided into eight (8) different groups, the matrices of one group bearing the different consonants (27) without vowels, and those of each of the remaining seven groups bearing the same consonants with a different vowel (7 in all), and that all of the eight different groups are controlled by a keyboard comprising a single group of finger keys, one for each of the different consonants, and seven different shift keys, one for each of the different vowels. The two hundred sixteen (216) characters rendered available by this arrangement will, with the aid of a few extra characters herein provided for, and with the aid of a few sorts matrices not so frequently needed, be enough to take care of all practical requirements. While, as stated at the outset, the Hebrew language employs twelve (12) different vowels, the seven herein dealt with are mainly responsible for the great number of characters required for Hebrew composition. However, the five excepted vowels have not been entirely neglected because the more frequently used consonants which carry them will either be taken care of as special characters or as sorts characters. Actually, the consonants carrying one of the vowels, those known as "daghehs" characters, are treated herein as consonants without vowels as before referred to.

Dealing with the special characters, that is to say, those not included within the two hundred sixteen (216) controlled by the twenty-seven finger keys and the seven shift keys, they are taken care of by adding to the keyboard thirty-three (33) additional finger keys which are adapted to serve as many different magazine channels. In reality, one of the keys (the em key) serves two different channels, making the total number of extra magazine channels thirty-four (34). These thirty-four extra magazine channels are added in different numbers to the twenty-seven channels of the eight different matrix groups before referred to, and the matrices stored in the extra channels of each group are connected to their appropriate finger keys in the keyboard under different conditions of adjustment as will be described later on. Since the extra finger keys

require as many different magazine channels, there is no saving in the number of keys so far as the special characters are concerned, but their addition to the keyboard gives rise to no handicap because, even including the extra keys, the total number comprising the keyboard is only sixty (60). Indeed, many of the extra keys included in the keyboard could be omitted if that were desirable; or the number could be reduced by placing two different characters on the same matrix and by placing two corresponding index characters on each key, a practice which is quite customary with numerals, punctuation marks, etcetera.

The splitting up of the magazine channels for the special characters in the manner just alluded to, has been resorted to in applying the invention to one of the regular commercial machines known as "Linotype Model 30". This machine is a double distributor mixing machine comprising two distributors, each serving a main magazine and an auxiliary magazine, and an assembling mechanism which permits the matrices from all the different magazines to be mixed in the same line for composition. Actually, the Model 30 Linotype includes two other main magazines and two other auxiliary magazines, provision being made whereby either the upper or the lower pair of main and auxiliary magazines may be brought into operative position to cooperate with the two distributors and the common assembling mechanism. The machine is thus especially suited to the present invention, because while one complete font is divided among four different magazines (two main magazines and two auxiliary magazines), the machine permits the composition in line of matrices from any one or all of the four magazines and will distribute the matrices automatically into any one or all of the four magazines. The second pair of main and auxiliary magazines would, in practice, be supplied with a different matrix font stored in the same group arrangement.

In applying the invention to a machine of the Model 30 class, the connection of the keyboard to one or another of the eight different groups of magazine channels is provided for in such manner that two of the shift keys will transfer control of the keyboard to two different groups of channels of the upper main magazine, a third shift key will transfer control to the channels of the upper auxiliary magazine, three other shift keys will transfer control to three different groups of channels of the lower main magazine, and the seventh shift key will transfer control to the channels of the lower auxiliary magazine, it being noted that the keyboard is normally connected to the intermediate group of channels of the upper main magazine which contains matrices bearing consonants without vowels. In transferring control of the keyboard from one group of magazine channels to another, some of the shift keys are required to perform dual operations, as will be more fully described in the detailed description to follow. Thus, in the present machine, there is a single series of main reeds which serve both main magazines, and there is likewise a single series of auxiliary reeds which serve both auxiliary magazines. The main series of reeds is divided into three (3) groups, one for each of the three groups of magazine channels of either of the main magazines. The keyboard is normally connected to the middle group of main reeds, but is provided with shifting devices by which the finger keys may be connected to

either of the other two groups. Two of the shift keys provide for this connection, so that when they are operated they are required to do no more. On the other hand, when the main series of reeds is adjusted into operative relation to the lower main magazine, three (3) other groups of magazine channels become available, and one of these groups of course will be served by the middle group of reeds which, as repeatedly stated, remain normally connected to the finger keys. Hence, one of the shift keys need only effect the adjustment of the reeds from the upper main magazine to the lower main magazine (which means a change of magazines) in order to connect the keyboard to the middle group of channels of the lower main magazine. In selecting either of the other two groups of magazine channels of the lower main magazine, however, it is not only necessary to adjust the reeds into operative relation to the lower magazine, but also to change the connection of the finger keys to the reeds of one or the other of the outside groups. In this instance, therefore, two of the shift keys are required to perform two distinct mechanical operations, one a reed adjustment, and the other a keyboard shift. The auxiliary series of reeds is operated from the middle group of the main reeds and this is effected by shifting the main reeds as a whole rearwardly to make the connection while permitting the keyboard to remain connected with the middle group of main reeds. Here the particular shift key is required only to effect the rearward adjustment of the main reeds. 35 When, however, the auxiliary reeds are adjusted into operative relation to the lower auxiliary magazine, there are two mechanical operations required, one to make such adjustment, and the other to establish the connection between the reeds and the middle group of main reeds. In all cases, whenever a shift key has been released, the control of the keyboard is shifted back to the middle group of main reeds, as well as to the middle group of channels of the upper main magazine, so that matrices bearing consonants without vowels may be released without the use of a shift key.

Referring to the drawings:

Fig. 27 is in the nature of a chart, showing the characters available by operation of the improved keyboard.

In the embodiment illustrated, the machine is equipped with four main magazines A and four auxiliary magazines B, all of which are of regular or standard form, i. e., the main magazines are provided each with ninety-one grooved channels, and the auxiliary magazines each with thirty-four grooved channels. The main and auxiliary magazines are mounted as usual in shift frames (not shown), which are arranged to be raised and lowered to bring either the upper two or the lower two magazines into operative position. While there are thus two distinct sets of magazines alternately usable, only two main and two auxiliary magazines are actually necessary, so far as the instant invention is concerned, and the present description may therefore be assumed to refer to that one set alone.

As previously stated, the machine is of the double distributor mixing type, which permits matrices from either of the two main or two auxiliary magazines to be assembled in line for the casting of a slug. The assembler mechanism herein illustrated includes for the main and auxiliary magazines, respectively, an assembler entrance having relatively fixed lower sections A¹ and B¹, relatively fixed upper sections A² and B², and pivoted sections or throats A³ and B³ (see Figs. 1 and 2) adjustable to two different positions, so as to make and break an operative connection with either the upper or lower magazines. When the pivotally mounted throats A³, B³ are in position to cooperate with the upper main and auxiliary magazines, the matrices X will, in response to the actuation of the keyboard, be released from their respective magazines and be deposited upon a traveling belt *a* for delivery to the usual assembler elevator (not shown); and, in like manner, when the throats are in position to cooperate with the lower main and auxiliary magazines, the matrices, when released from such magazines will likewise be deposited upon the belt *a* for delivery to the assembler elevator.

The matrices X are released from the main magazines A (see Fig. 1) under the control of escapements C by a series of vertical reeds C¹, a corresponding series of horizontally arranged and pivotally mounted levers C² overlying the reeds, and a series of shorter substantially vertical reed sections C³ slidably mounted on the throat A³. When the throat A³ is operatively associated with the upper magazine, the escapements of the latter are actuated by the short reed sections C³ through the medium of two series of short interponents *c*, c¹ connected together by intermediate swivel plates c²; whereas, when the throat is operatively associated with the lower magazine, the escapements of the latter are actuated by the short reed sections directly. At their lower ends (Fig. 5), the reeds C¹ terminate above a corresponding series of short reed sections C, which latter are operated by a set of pivoted yokes D arranged in two banks and provided with cams or eccentrics D¹ cooperating with a pair of underlying power driven rolls D². Trip dogs D³ control the operation of the yokes D and a common series of vertical key-controlled slides E actuate the trip dogs. The arrangement and the method of operation of the foregoing parts are old and are described in detail in the copending application of Frolander and Burt, Serial No. 139,436, filed April 28, 1937. Suffice it to say here that, when a yoke D is tripped by a slide E, the free end thereof will be caused to rise and, through a short reed section C⁴, lift the associated reed C¹, which in turn will actuate the escapement of the corresponding channel of the magazine with which the pivoted assembler throat A³ is associated at the time.

Insofar as the auxiliary magazines B are concerned, the manner in which the matrices are released therefrom is the same as above described, except that the series of vertical reed C⁵ associated with said magazines are actuated through a series of bails C⁶ (see Figs. 1 and 2) from certain of the reeds C¹ associated with the main magazines.

As stated at the outset, the Hebrew alphabet consists of 22 pure or intermediate consonants used alone or in association with vowels, 5 "dagheesh" used alone or in association with vowels and which, for the purpose of this invention, are treated the same as the pure or inter-

mediate consonants, 5 final consonants used only without vowels, and 9 general and 3 special vowels, only 7 of which are necessary for most practical purposes. Since the characters most commonly used are thus 216 in number, these have been arranged in eight groups (see Fig. 27) of 27 characters each (22 intermediate consonants and 5 dagheesh), one group (group 2) including the consonants and dagheesh without vowels, and the other groups including the consonants and dagheesh with vowels, which vowels are the same in the individual groups, but differ as between the groups. Thus, by referring to Fig. 27, it will be noted that all of the 30 characters in group 2, with the exception of Nos. 7, 12 and 25 (later referred to) or 27 different characters in all, are repeated throughout the other groups; and when reference is hereinafter made to the various character groups, numbered 1 to 8, it will be understood that only those 27 characters, thus repeated in the different groups, are included in the reference. The other characters will be dealt with separately.

In accordance with the present invention, the two main magazines A each have their channels divided into three groups (Fig. 26), the group at the left comprising thirty channels, the center group thirty channels, and the group at the right thirty-one channels, thus accounting for all the ninety-one channels in each of the main magazines. In the upper main magazine, there are stored in the channels of the left group the matrices of group 1, in the channels of the center group the matrices of group 2, and in the channels of the right group the matrices of group 3. The matrices of group 4 are stored in the channels of the upper auxiliary magazine B, which may be considered as another group of magazine channels. In the lower main magazine, there are stored in the channels of the left group the matrices of group 5, in the channels of the centre group the matrices of group 6, and in the channels of the right group the matrices of group 7. The matrices of group 8 are stored in the channels of the lower auxiliary magazine, which may be considered as still another group of magazine channels. Throughout the magazine channels of the eight different groups, the matrices are stored in like manner (although they need not be) according to character.

The matrices (see Fig. 23) are of the usual form, although herein each is provided with only one routing notch X¹, and consequently one character, so that each channel throughout the two main and two auxiliary magazines will be devoted to a different character of the matrix font.

Since each of the eight matrix groups contains but twenty-seven characters that are repeated throughout the various groups, there will be three extra channels in each magazine group allotted to matrix groups 1, 2, 5 and 6, four extra channels in each magazine group allotted to matrix groups 3 and 7, and seven extra channels in each magazine group allotted to matrix groups 4 and 8. In the left groups of both main magazines, the three extra channels are at the right and are devoted to matrices bearing punctuation marks. In the center groups of the main magazines, the three extra channels are the 7th, 12th and 25th and are devoted to matrices bearing final consonants or special characters, such as those with special vowels. In the right groups of the main magazines, the four extra channels are at the right and are devoted to matrices, some

bearing punctuation marks, and other special characters, while one channel in each of these sections is devoted to the em space. In each of the auxiliary magazine groups, the seven extra channels are at the right and contain matrices, some bearing numerals, others punctuation marks, one the dollar sign, and one a final consonant. In order to simplify the description of the invention, the characters in the different groups which have the consonants in common (the 27 previously mentioned) will be termed regular characters, while the others, including the punctuation marks, final consonants, consonants with special vowels, numerals, etc., will be termed special characters.

The keyboard F of the machine (see Fig. 4) includes sixty matrix releasing finger keys F¹, a spacer releasing key G, and seven shift keys G¹, G³, G⁴, G⁵, G⁶, G⁷ and G⁸. These shift keys bear index characters corresponding to the vowels of matrix groups 1, and 3 to 8, respectively, and twenty-seven of the finger keys F¹ bear index characters corresponding to the regular characters of matrix group 2, i. e., consonants without vowels. These twenty-seven finger keys, together with keys Nos. 7, 12 and 25, which bear index characters corresponding to the three special characters of matrix group 2, make up the first thirty keys of the keyboard. The remaining thirty keys, with the exception of key No. 34, which is the em key, bear index characters corresponding to the remaining special characters, e. g., keys Nos. 31 to 33 the special characters of matrix group 1, keys Nos. 35 to 37 the special characters of matrix group 3, keys Nos. 38 to 44 the special characters of matrix group 4, keys Nos. 45 to 47 the special characters of matrix group 5, keys Nos. 48 to 50 the special characters of matrix group 6, keys Nos. 51 to 53 the special characters of matrix group 7, and keys Nos. 54 to 60 the special characters of matrix group 8.

The group of twenty-seven keys bearing the regular characters is hereinafter referred to as the consonant key group, and it is common to all the eight different matrix groups. Normally, the consonant key group is connected for the release of the corresponding matrices of group 2, this being the group whose matrices bear consonants without vowels. When, however, during the course of composition, the operator desires to select a consonant with a vowel, he first presses the shift key bearing the vowel, and then the key bearing the consonant. Upon the operation of the vowel shift key, the consonant key group is automatically connected for the release of the matrices from the corresponding vowel group, so that when the consonant key is depressed, a matrix bearing such a vowel carrying consonant will be released from the appropriate magazine and assembled in line.

Since the matrices bearing the special characters are controlled in their release by separate keys, entirely divorced from the consonant key group, they can, under certain conditions, be released even though the consonant key group is connected for the release of matrices from a group of magazine channels different from that in which the special characters are stored. Thus, when the consonant key group is connected for the release of matrices from any one of matrix groups 1, 2 or 3 of the upper main magazine, not only will those keys which release the special matrices of the selected group be operable, but also those keys which control the release of the special matrices of the other two groups. Again,

when the consonant key group is connected for the release of matrices from matrix group 4 in the auxiliary magazine, not only the keys which control the release of the special matrices of that group, but also those keys which control the release of the special matrices of matrix groups 1, 2 and 3, will be operable. Similar conditions exist with reference to the keys controlling the release of the special matrices of the different groups in the lower magazines. Thus, when the consonant key group is connected for the release of the corresponding matrices of any one of the matrix groups 5, 6 or 7, of the lower main magazine, the keys for controlling the release of the special matrices of any of these groups will be operable; and likewise, when the consonant key group is connected for the release of matrices of group 8 in the lower auxiliary magazine, not only will the keys controlling the release of the special characters of that group be operable, but also the keys controlling the release of the special characters of all three groups in the upper main magazine. Fig. 27 sets forth the characters, both regular and special, which are available when the consonant key group is connected for releasing matrices from any selected one of the eight different matrix groups and, at the right under the heading "extra characters", the special characters (not of the selected group but of other groups) which are available for that particular connection of the consonant key group. It might be stated here that for any selected connection of the consonant key group, all of the keys corresponding to the special characters not available will be either idle or locked against operation.

In order that skill in operating the keyboard may be readily acquired, different colors may be used for the shift keys and for those special character keys which can only be used when a particular shift key is operated. Thus (Fig. 4), character keys Nos. 1 to 37 are white, as are also shift keys G¹ and G³; character keys Nos. 38 to 44 and shift key G⁴ are yellow; character keys Nos. 45 to 53 and shift keys G⁵, G⁶ and G⁷ red, and character keys Nos. 54 to 60 and shift key G⁸ blue.

The reeds C¹ for effecting the release of the matrices from the main magazine A are ninety-one in number, while the reeds C⁵ for effecting the release of the matrices from the auxiliary magazines B are thirty-four in number, there thus being one reed for each channel of a main and an auxiliary magazine. To facilitate the description, the reeds C¹ associated with the main magazines have been divided into three groups (see Fig. 26), designated, respectively, group O, group P, and group Q. The reeds of group O are operative to effect the release of matrices from matrix groups 1 and 5, those of group P to effect the release of matrices from matrix groups 2 and 6, and those of group Q to effect the release of matrices from matrix groups 3 and 7. The reeds C⁵ associated with the auxiliary magazines have been designated group R and are operative to effect the release of matrices from matrix groups 4 and 8.

As previously stated, the twenty-seven keys of the consonant key group are normally connected to operate the reeds which effect the release of the corresponding matrices of matrix group 2, being all of the reeds of group P with the exception of Nos. 7, 12 and 25.

Upon the operation of the shift key G¹, however, (which is the one bearing the vowel indica-

tive of matrix group 1), the consonant key group is disconnected from the reeds of group P and connected with the corresponding reeds of group O, being all of the reeds of this group with the exception of the three at the right, which are associated with the magazine channels containing the special characters of said matrix group 1.

When the shift key G³ bearing the vowel indicative of matrix group 3 is depressed, the consonant key group is disconnected from the reeds of group P and connected with the corresponding reeds of group Q, being all of the reeds of that group, with the exception of the four at the right, which are associated with the magazine channels containing the special characters of said matrix group 3.

When the shift keys G⁵ or G⁷ bearing the vowels indicative of matrix groups 5 and 7 are depressed, the consonant key group is disconnected from the reeds of group P and connected with the corresponding reeds of group O and group Q, respectively, as in the case of the shift keys G¹ and G³, again excepting the reeds of these groups associated with the extra magazine channels containing the special characters. The depression of the shift keys G⁵ or G⁷, however, will also result in shifting the pivoted assembler throat A³ from its upper magazine receiving position to its lower magazine receiving position, so that the matrices from group 5 or 7 can be assembled by the operation of the consonant key group.

When the shift key G⁶ bearing the vowel indicative of matrix group 6 is depressed, the connections of the consonant key group with the reeds of group P remain as before but the pivoted assembler throat A³ is shifted to its lower magazine position so as to permit the assembly of the matrices of group 6.

Upon the depression of either one of the shift keys G⁴ or G⁸ bearing the vowels indicative of matrix groups 4 and 8, the entire bank of main reeds C¹ is swung rearwardly about their lower ends as pivots. This operation effects the connection of the twenty-seven reeds of group P (normally operated by the consonant key group) with the bails C⁶, which in turn are connected with the corresponding reeds of group R. The depression of shift key G⁴ has no effect upon the pivoted assembler throat B³ associated with the auxiliary magazines but the depression of shift key G⁸ does, causing the throat to swing to its lower magazine receiving position. Hence, the matrices can be released from either one of groups 4 or 8 by the operation of the keys of the consonant key group, depending upon which of said shift key G⁴ or G⁸ is depressed.

When the main bank of reeds C¹ is shifted rearwardly, not only the twenty-seven reeds of group P but in addition fourteen of the reeds of group P will be connected with the bails C⁶, seven of the latter reeds operating the last seven reeds at the right of group R when the shift key G⁴ for matrix group 4 is depressed, and the other seven reeds operating the same last seven reeds of group R when the shift key G⁸ for matrix group 8 is depressed. These connections are shown diagrammatically in Fig. 24, as are also the connections between the extra reeds in groups O, P and Q (designated, respectively O¹, P¹ and Q¹) and the corresponding special character keys.

Upon the release of any shift key, the original connections between the consonant key group and the reeds of group P are restored, the pivoted assembler throats returned into operative relation with the upper magazines, and the bank of

main reeds returned to normal position, the conditions, of course, depending upon the particular shift key operated.

Before proceeding with the description of the manner in which the control of the consonant key group is shifted to the different matrix groups, it is thought best at this point to describe somewhat in detail the construction of the keyboard itself. In many respects, it is the same as disclosed in the recently issued patent to Burt No. 2,090,028, but in view of the changes made in adapting it to the present invention, a rather complete description is thought to be desirable.

The framework of the keyboard (see Figs. 4 and 5) comprises generally a main supporting base frame H, a sheet metal keyboard casing H¹, a pair of side bracket plates H² arranged within the casing H¹, and an auxiliary box-like member H³, which latter is located adjacent the rear wall of the casing H¹ and is fastened to upright side posts H⁴ rising from the base frame H.

The finger keys F¹ of the keyboard F are arranged in four rows or tiers (there being fifteen in each row) and are pivoted between their ends on fixed horizontal cross rods F³ mounted in the bracket plates H². At their rear ends (see Fig. 5), the finger keys F¹ of each row engage beneath bent-over nose portions j formed at the forward ends of a set of actuating levers J, through which the keys are operatively connected to a corresponding set of U-shaped rocking bails J¹, there being four sets of bails for the four rows of finger keys, and as many bails in each set as there are keys in the respective rows. As best shown in Fig. 5, the different sets of bails J¹ are arranged one above the other in the auxiliary frame member H³ and are mounted on separate pivot rods J², with the cross members j¹ of the individual bails J¹ resting upon teeth or projections j² formed on the upper edges of the actuating levers J. The teeth j², as will be observed in Fig. 5, are differently located, so that each bail of the four sets may be operated by a separate lever J when the corresponding finger key F¹ is depressed. To avoid friction between their points of contact with the bails, the levers J are mounted at their rear ends on the same pivot rods J² and are themselves supported at the front in a vertical slotted guide plate H⁷, which forms the front wall of the auxiliary frame member H³. As the bails J¹ are rocked upwardly by the depression of the finger keys, motion is imparted thereby through overlying levers J³ to a series of vertical actuating rods K, and thence to the controlling slides E in a manner about to be described.

The levers J³ for the different bail sets, like the levers J, are mounted at their rear ends on the pivot rods J² and at the front present shoulders j³ which engage beneath corresponding lugs k projecting from the rear edges of the actuating rods K. On their lower edges, the levers J³ are formed with teeth or projections j⁴ which, like the teeth j² of the levers J, are differently located to engage the cross members j¹ of the different bails J¹. The arrangement is such that, as a bail is rocked upwardly by a finger key, it will raise those overlying levers J³ whose teeth engage it, and they in turn will lift the corresponding actuating rods K. At their lower ends, the rods K are formed with ears or lugs k¹ and are adapted to actuate the controlling slides E through the medium of a series of fore-and-aft bars L, the

latter being arranged with their front ends beneath the slides E.

The controlling slides E are properly guided in their vertical movements by upper and lower comb plates or bar sections H⁹, which constitute part of the keyboard frame, and the rods K are similarly guided by upper and lower comb plates H¹⁰. The lower comb plate for the actuating rods K (Fig. 5) serves also as a guiding member for the selecting bars L, being formed with a slotted vertical section L⁴ through which said bars extend.

While the bails J¹ and the underlying levers J correspond in number to the keys of the keyboard and the controlling slides E in number to the total number of reeds of groups O, P and Q, that is, 91 in all, the overlying levers J³ and the rods K are one hundred and fourteen in number, this difference being due to the fact that, insofar as the keys of the consonant group are concerned, each key controls, through its associated bail, three different rods K and three different controlling slides E, said three controlling slides each actuating one of the reeds in each of the groups of reeds O, P and Q. This accounts for twenty-seven of the keys, eighty-one of the controlling slides E and eighty-one of the rods K. Then, of course, there are thirty-two special character keys, nine of which (Nos. 7, 12, 25, 31 to 33 and 35 to 37) control, through nine different rods K, nine controlling slides E actuating nine different reeds, i. e., three in group O, three in group P, and three in group Q, when any one of the matrix groups 1, 2 or 3 is in use. Nine different keys (Nos. 45 to 53) control, through nine different rods K, the same nine controlling slides E, when any one of matrix groups 5, 6 or 7 is in use. The key controlling the release of the em space, accounts for one rod K and one controlling slide E, these elements being active to release the em space at any time. Fourteen keys (Nos. 38 to 44 and 54 to 60) operate to release the matrices of groups 4 and 8. These keys control, through fourteen individual rods K, fourteen of the controlling slides E associated with the reeds of group Q, and which are also used when the consonant key group is connected for the release of matrices in groups 3 and 7. In other words, there is a group of twenty-eight rods K, fourteen of which, under one condition, operate certain slides E associated with the reeds in group Q, and fourteen different rods K that will operate the same slides under a different condition. This accounts for all of the sixty keys, the ninety-one controlling slides E and the one hundred and fourteen rods K.

As before stated, the controlling slides E are actuated by the rods K through the medium of a series of fore-and-aft bars L. Insofar as the different reeds groups controlling the release of regular characters are concerned, these slides act as selecting elements, whereby the different groups can be connected for operation by the common consonant key group upon the operation of the various shift keys. For this purpose, the selecting bars L, associated with the slides E for controlling the twenty-seven reeds in each of the different groups O, P and Q, are formed in their lower edges with different tooth and notch combinations l, l¹ adapted to cooperate in different ways with the underlying ears or lugs k¹ on the rods K, depending upon the fore-and-aft position of adjustment of the bars L. Thus in Figs. 13, 14 and 15, there are illustrated three slides E, which, under different conditions, can be actu-

ated by a single bail J¹ under the control of a single key of the consonant group, together with the bars L through which the selection of the slides is effected.

In Fig. 13, there is illustrated a bar L characteristic of those controlling the slides E which operate the reeds of group P, reference being now had to only the twenty-seven reeds in this group for releasing the regular characters. The bars L have three different positions of adjustment in a fore-and-aft direction, the normal position being shown in this figure. Here, it will be seen that the tooth l directly overlies the lug k¹ of the rod K. Consequently, when the bail J¹ is raised through the operation of the corresponding finger key, the resultant movement of the rod K will be transmitted through the lug k¹ to the slide E, so that the corresponding reed of group P will be actuated. However, when the bar L is shifted either forward or backward, one or another of the notched portions thereof will overlie the lug k¹ on the rod K, so that, under these conditions, the upward movement of the rod K will be an idle one.

In Fig. 14, there is illustrated a bar L characteristic of those associated with the slides for operating the reeds in group O. The slide here is shown in its forward position, with the lug k¹ on the rod K engaging the lower edge of said bar. Consequently, when the bail J¹ is raised by the operation of the corresponding finger key, the resultant upward movement of the rod K will be transmitted to the bar L to raise the slide E; whereas, when the bar L is returned to its normal position, or is moved to its rearward position, the notch in the lower edge thereof will overlie the lug k¹, so that, under these latter two conditions, the upward movement of the rod K will be an idle one.

In Fig. 15, there is illustrated a bar L characteristic of those associated with the slides E which control the actuation of the reeds in group Q, with the exception of the fourteen slides which, in addition, control the release of matrices bearing special characters in the auxiliary magazines. This particular bar L is shown in its rearward position, wherein the tooth in the lower edge thereof overlies the lug k¹ on the rod K. Consequently, when the bail J¹ is raised upon the operation of the corresponding finger key, the resultant upward movement of the rod K will be transmitted through the bar L to the slide E to effect the operation of the corresponding reed. When the bar L is in its normal or its forward position, the notched portion thereof, which is wide enough for the purpose, will overlie the lug k¹, so that the upward movement of the rod K under those conditions will be idle.

Hence, as regards those slides E which are operated from the consonant key group, the selecting bars L therefor take three different forms and have each three different positions, that is to say, a normal or central position wherein the slides associated with the reeds of group P will be operative while those associated with groups O and Q are inoperative, a forward position wherein the slides E associated with the reeds of group O will be operative while those associated with groups P and Q will be inoperative, and a rearward position wherein the slides associated with the reeds of group Q will be operative and those associated with groups O and P inoperative.

The slides E which control the release of the special characters, that is, all those released through the operation of the finger keys other

- than the finger keys of the consonant key group, are operated in the same manner as those previously described, except that the bars L, through which they are actuated, are somewhat different. 5 Thus, the slides E, which are active in releasing the special characters in both the upper and lower main magazines, are actuated each by two different rods K (see Fig. 18), one of which is operated by a special key when the pivoted assembler throat A³ is operatively connected with the upper magazine, and the other by a different special key when the pivoted assembler throat is operatively connected with the lower magazine. 10 The rods K actuate the slide E through a common bar L, which is plain in its lower edge, so that, irrespective of the fore-and-aft position of adjustment of the bar L, the slide E will be actuated upon the upward movement of either one of the rods K. 15
- 20 The fourteen slides E corresponding to the reeds of group Q, which, under certain conditions, are controlled by keys of the consonant key group and, under other conditions, by special keys for releasing from the auxiliary magazines the matrices bearing the special characters, are also actuated (see Fig. 12) each by two different rods K through the medium of a common bar L. The tooth and notch combination of this bar includes two teeth l², l³, the forward teeth l² cooperating 25 with the protuberance k¹ of the bar K controlled by a special character key, and the second tooth l³ cooperating with the protuberance k¹ on the bar K controlled by a key of the consonant key group. When the bar L is in its normal position of adjustment, the tooth l² immediately underlies the protuberance k¹ of its associated rod K, while the tooth l³ is just forward of the protuberance k¹ of its associated rod K. According to this arrangement, when the bar L is in its normal position of adjustment, the slide E can be actuated by the upward movement of the rod K controlled from the corresponding special character key, whereas the upward movement of the rod controlled from the corresponding key of the consonant key group will be idle. In the forward position of adjustment of the bar L, the upward movement of both rods K will be idle. In the rearward position of adjustment of the bar L, the upward movement of the rod K controlled by the special character key will be idle, whereas the upward movement of the rod K, controlled from a key of the consonant key group, will be operative to actuate the slide E. In other words, insofar as the latter rod K is concerned, the bar 50 L cooperates with it in the same manner as the other bars L associated with the slides E corresponding to the other reeds of group Q, which are operated only by keys of the consonant key group.
- 60 The selecting bars L are moved to their different positions of adjustment through the medium of a shift frame S (see Figs. 5 and 7), which includes a pair of side arms S¹ suspended from an overhead pivot rod S² and a lower transverse connecting rod L¹ to which the selecting bars L are pivoted at their rear ends. During the adjusting movement of the shift frame S, the selecting bars L are sustained in operative relation to the lugs k¹ of the rods K, and also in engaging 65 relation with the lower ends of the controlling slides E, by a horizontal plate H⁸ which is arranged beneath the bars and secured to the side walls of the auxiliary frame member H³.
- 70 The devices for shifting the frame S (see Figs. 4, 5 and 7) include a fore-and-aft slide bar S³ arranged beneath the base frame H and connected thereto for endwise movement by a screw and slot s at the front and by a sustaining guide bracket h³ at the rear. The bar S³ (as best shown in Figs. 5 and 7) is connected at its rear 5 end to the shift frame S by means of a coupling S⁴ and is held resiliently in its intermediate position against movement in either direction by a pair of spring-actuated levers S⁵, S⁶, which are disposed transversely of and beneath the bar S³ 10 in engaging relation to a plate S⁷ secured to the lower face of said bar (see also Fig. 4). The levers S⁵, S⁶ are pivoted, respectively, at s¹, s² to the base frame H and are held apart in parallel spaced relation in opposition to a connecting spring S⁸ by a fixed stop plate S⁹, against which their free ends engage.
- 75 The rearward movement of the bar S³ is effected by a horizontally disposed lever S¹⁰ through a vertical slide plate S¹¹, and the forward movement of the bar is effected by a similar lever S¹² through a corresponding vertical slide plate S¹³. The manner in which the slide plates S¹¹ and S¹³ are actuated to move the shift frame will be later described. The levers S¹⁰ and S¹² (see Fig. 4) are 15 intermediately pivoted to the base frame H on vertical axes s³, s⁴ and are arranged end to end with their nose portions seated in a recess s⁵ of a block S¹⁴ secured to the top of the bar S³.
- 80 As best shown in Figs. 4 and 5, the slide plates S¹¹, S¹³ are mounted in fixed bracket members H¹¹ of the framework and are held resiliently against upward movement by pull springs S¹⁵ connected to the upper ends of the plates and anchored to pins s⁶ projecting laterally from the 35 members H¹¹. The pins s⁶ engage in corresponding slots s⁷ formed in the slide plates S¹¹, S¹³, and sustain the plates vertically in a normal downward position against the tension of the springs S¹⁵. At the lower ends, the plates S¹¹, S¹³ are 40 provided with anti-friction rollers s⁸ which are arranged to engage curved or cam surfaces s⁹ formed on the contiguous end portions of the aforementioned horizontal levers S¹⁰ and S¹². The cam surface s⁹ of the lever S¹² engages the 45 anti-friction roller s⁸ of its associated slide at the front, whereas the corresponding cam surface of the lever S¹⁰ engages the anti-friction roller of its respective slide at the rear.
- 85 According to the foregoing arrangement, as 50 the vertical slide S¹¹ at the left is raised, the roller s⁸ thereon will rock the lever S¹⁰ in a clockwise direction, so as to move the bar S³ forwardly against the tension of the pull spring S⁸ and thus swing the shift frame S in the same direction to 55 its forward adjusted position, which, it will be recalled, is the adjustment wherein the consonant key group is connected for operating the reeds of group O. As the slide S¹¹ is lowered, the bar S³ and the shift frame S will be restored to their 60 original positions by the spring S⁸ acting through the lever S⁶. And likewise, as the vertical slide S¹³ at the right is raised, the anti-friction roller s⁸ thereon will rock the lever S¹² in a clockwise direction, so as to move the bar S³ rearwardly 65 against the tension of the pull spring S⁸, and thus swing the shift frame S in the same direction to its backward adjusted position, which, it will be recalled, is the position of adjustment wherein the consonant key group is connected 70 for operating the reeds of group Q; and as the slide S¹³ is lowered, the bar S³ and the shift frame S will be restored to their original positions by the spring S⁸ acting through the lever S⁵.

75 It will now be clear how the control of the con- 75

sonant key group is shifted to release the matrices of group 1 and group 3 under the control of the shift keys corresponding to these groups. Thus, the shift key G^1 corresponding to matrix 5 group 1 (see Figs. 4, 7 and 21) is fulcrumed adjacent its center on a transverse pivot rod G^9 secured at its ends in the side plates H^2 of the keyboard frame. At its rear end, the shift key engages beneath a stud s^{10} projecting laterally from 10 the vertical slide S^{11} , so that, as the key is depressed, the slide will be raised to effect the forward movement of the shift frame S in the manner just described. This operation will bring the reeds of group O under the control of the consonant key group and, since the pivoted assembler throat is in its normal position, i. e., associated with the upper magazine, the matrices of group 1 can be released by the operation of the keys F^1 of the consonant key group. And when 15 the shift key G^1 is released, the vertical slide S^{11} will be lowered, under the action of its pull spring S^{15} , so that the shift frame will be restored to normal position.

The shift key G^3 , corresponding to matrix 20 group 3, is fixed at the left end of a sleeve G^{10} rotatably arranged on a transverse rock shaft G^{11} , journalled at its ends in the side plates H^2 , the sleeve being provided at its right end with an arm G^{12} fixed thereto and which extends rearwardly and engages under a stud s^{11} extending laterally from the vertical slide S^{13} , so that, as the key is depressed, the sleeve G^{10} will be rotated and the arm G^{12} caused to raise the slide S^{13} , thus moving the shift frame S rearwardly to connect 25 the consonant key group with the reeds of group Q and, here, again, because of the position of the pivoted assembler throat, these reeds will effect the release of the matrices of group 3 upon the operation of the keys of the consonant key group. 30 When the shift key G^3 is released, the slide S^{13} will be lowered, by the action of its associated spring S^{15} , allowing the shift frame to be restored to normal position.

Similar operations are accomplished through 35 the actuation of the shift keys G^5 and G^7 for matrix groups 5 and 7, the shift key G^5 for group 5 being mounted near its center on the rock shaft G^{11} and having its rear end engaging beneath the stud s^{10} on the vertical slide S^{11} , and the shift key G^7 for group 7 being likewise mounted near the center on the rock shaft G^{11} and having its rear end engaging beneath the stud s^{11} on the vertical slide S^{13} . Consequently, when the shift key G^5 is depressed, it will raise the slide S^{11} to 40 move the shift frame S to its forward position of adjustment, wherein the keys of the consonant key group will be connected for operating the reeds of group O in the same manner as when the shift key G^1 is depressed; whereas, when the shift key G^7 is depressed, it will raise the slide S^{13} to move the shift frame to its rearward position of adjustment, wherein the keys of the consonant key group are connected to the reeds of group Q in the same manner as when the shift key G^3 is depressed. It will be recalled, however, that, in order to release the matrices of group 45 5 and group 7, not only must the reeds of group O or group Q, respectively, be connected for operation by the consonant key group, but in addition the pivoted assembler throat A^3 must be moved from its normal position in operative association with the upper main magazine to its other position in operative association with the lower main magazine. This adjustment of the 50 pivoted assembler throat A^3 is accomplished 75

through the medium of power mechanism controlled from the shift keys G^5 and G^7 simultaneously with the adjustment of the shift frame S .

The power mechanism is also operative to adjust the pivoted assembler throat under the control of the shift key G^6 which, at its rear end, is pinned to the rock shaft G^{11} . This is the only adjustment effected by the shift key G^6 , however, since the matrices bearing the regular characters of matrix group 6 are released by the same 10 group of reeds as the regular characters of group 2, for the operation of which the consonant key group is normally connected.

The power mechanism, for shifting the pivoted assembler throat A^3 , is shown in Figs. 3, 8, 9 and 15 11. As will be observed, the throat is fixed to a rock shaft A , on the right end of which there is pinned an arm A^5 connected at its free end, by a rod A^6 to a lever A^7 (see Fig. 8) operated by a cam T rotatably mounted on a shaft T^1 . Integrally connected with the lever A^7 is a forwardly projecting arm A^8 connected through the medium of a link A^9 with another pivotally mounted arm A^{10} equipped at its front end with an anti-friction roller A^{11} arranged to track in a groove T^2 20 formed in the face of the cam T . The groove T^2 is formed with four high portions t spaced apart at intervals of 90° and four intermediate low portions t^1 . In the normal position of the cam T , as shown in Fig. 8, the cam follower or 25 roller A^{11} is located in a high portion t of the groove and, under such conditions, the throat A^3 completes an operative connection between the upper magazine A and the lower fixed section A^1 of the assembler entrance. However, when the cam T is rotated through an angle of 45° , a low portion t^1 of the cam will arrive opposite the cam follower and, in doing so, will turn the lever A^7 in a counterclockwise direction (looking at the machine from the right), thereby pulling down on the rod A^6 which, in turn, swings the throat A^3 to a position wherein it completes an operative connection between the lower magazine and the fixed lower section of the assembler entrance. When the cam is again rotated 30 40 45 through an angle of 45° in the same direction, the lever A^7 will be turned in the opposite direction to restore the throat to its original or normal position. In order to insure the full movement of the throat into cooperative relation with the lower magazine, a tension spring A^{12} , having an anchorage in a fixed part of the machine, pulls down on the arm A^5 , so as to take up any play that might exist in the operating connections. 50

The rotation of the cam T through increments of 45° is effected through the medium of a pawl and ratchet mechanism T^3 , the pawl T^4 being pivotally arranged on a member T^5 rotatably mounted on the shaft T^1 , and being arranged to engage ratchet teeth T^6 in fixed association with the cam. The ratchet teeth are eight in number, and the pawl is held in engagement therewith by a spring t^2 connected thereto and having an anchorage in an extension of the member T^5 with which it is associated. Consequently, when the member T^5 is turned from the position shown in Fig. 8, through an angle of 45° , it will, through the pawl and ratchet mechanism, actuate the cam an equivalent amount and, when the member is released, it will be returned to normal position under the influence of a spring t^3 connected to the member and anchored in a fixed part of the machine. The normal position of the member T^5 is determined by a banking stop t^4 formed integral with the supporting frame and 55 60 65 70 75 75

against which a projecting portion of the member abuts during the return movement of the latter. During such return movement, the pawl T⁴ will merely slide back along the teeth T⁶ to a position wherein it will again be ready to transmit motion to the cam T by the engagement of the next tooth.

As thus far described, the parts of the power mechanism and their mode of operation are the same as set forth in the Frolander and Burt application, Serial No. 139,436 before referred to or as set forth in the Hayward application, Serial No. 125,023, filed February 10, 1937. The present invention is primarily concerned with the control of the power mechanism from different shift keys, as will now be described.

The member T⁵ is operated to effect the rotation of the cam through power devices controlled from the shift keys G⁵, G⁶ and G⁷. The power devices (see Figs. 8, 9 and 11) include a continuously rotating roller T⁷ and a cam T⁸ eccentrically mounted in a yoke T⁹ which is pivoted at one end in the fixed frame and normally held by a trip dog T¹⁰ engaging beneath its free end in a position in which the cam is above and out of contact with the roller. When the shift keys are depressed, they will, through connections hereinafter described, raise a slide T¹¹ to trip the lever T¹⁰, thereby releasing the yoke and permitting the cam T⁸ to fall by gravity into engagement with the roller T⁷. The cam T⁸ is thus rotated through a single revolution, much in the same manner as the reed operating cams of the main keyboard; and, after one revolution of the cam, its supporting yoke will again come to rest on the lever T¹⁰, with the cam out of engagement with the roller T⁷.

The slide T¹¹ is formed at its upper end with spaced sections t⁵ and t⁶, one engaging between fixed abutments, so as to guide the slide in its movement, and the other, which is formed with a double bevelled nose portion t⁷, engaging the trip lever T¹⁰. When the shift keys G⁵, G⁶ and G⁷ are fully depressed, the nose portion t⁷ of the slide, having tripped the lever T¹⁰, will be located opposite a recess t⁸ formed in the rear edge of the trip lever (see Fig. 11), which allows sufficient clearance for the trip lever to return to its normal position, wherein it will support the cam out of engagement with the roller, despite the fact that the slide is held in its raised position due to the depressed condition of the shift keys.

During the rotation of the cam T⁸, the cam yoke T⁹ is rocked upwardly and, at its rear end, engages a short overlying vertical slide T¹² through which the cam actuating movement of the member T⁵ is effected.

The pivoted assembler throat is automatically returned to its normal position (in association with the upper magazine) after the operator has finished composing from either one of matrix groups 5, 6 or 7 upon the release of the corresponding shift key G⁵, G⁶ or G⁷. Upon the release of the keys, the slide T¹¹ is moved downwardly from its raised position, whereupon the nose portion t⁷ thereof, by its lower bevelled surface, will again actuate the trip dog T¹⁰ to trip the cam yoke T⁹, thus inaugurating the same operation as when the slide T¹¹ was raised by the depression of the shift keys; or, to repeat, the pawl and ratchet mechanism T³ is moved to rotate the cam T through another angle of 45°, thereby bringing a high portion of the cam opposite the follower A¹¹, so as to return the pivoted assembler section A³ back to its normal position.

In order to prevent overrunning of the cam T (see Figs. 8 and 11), as in the two co-pending applications, there is provided a pawl T¹³ carried at the end of a centrally pivoted lever T¹⁴, spring-urged toward the cam T. The pawl T¹³ is pivotally mounted on the lever T¹⁴ and adapted to engage in one or another of a plurality of recesses T¹⁵ spaced about the peripheral edge of the cam in such manner that there will be a recess in registry with the pawl when the cam is in any position corresponding to an operative position of the pivoted assembler throat A³. When the trip lever T¹⁰ is turned to trip the cam yoke T⁹, the initial movement thereof will, through a link T¹⁶, connected thereto and to the lever T¹⁴ and prior to the engagement of the cam T⁸ with the roller T⁷, withdraw the pawl T¹³ from the recess T¹⁵ in which it happens to be seated at the time and, in order that the pawl does not again enter the same recess prior to the time the rotation of the cam T is inaugurated, it is swung under spring tension to the dotted position shown in Fig. 11, where it will rest upon the outer peripheral edge of the cam. As the cam T completes the range of movement required to shift the pivoted assembler throat from one operative position to another, another recess in the cam will arrive opposite the pawl T¹³, which is immediately entered thereby under the action of the spring-urged lever T¹⁴. Since the pawl T¹³ is moved out of the recesses directly by the action of the trip lever T¹⁰, it is apparent that this will occur both upon the upward movement of the slide T¹¹, when one or another of the shift keys G⁵, G⁶ or G⁷ is depressed, and also upon the downward movement of the slide when the depressed shift key is released.

The connections whereby the shift keys G⁵, G⁶ and G⁷ control the power mechanism for effecting the adjustments of the pivoted assembler throat A³ will now be described. It will be recalled that these shift keys are mounted on the rock shaft G¹¹, the arrangement being such that, as the keys are depressed, they will rock the shaft in a counterclockwise direction, looking at the keyboard from the right. While the shift key G⁶ is pinned rigidly to the rock shaft, the mounting of the keys G⁵ and G⁷ is such that either one will remain stationary when the other is operated, since these keys also operate the shift frame S, one in the forward direction and the other in the rearward direction. Thus, referring to Figs. 21 and 22, it will be seen that the shaft G¹¹ in the vicinity of the keys G⁵ and G⁷, is provided with feathers g extending into segmental recesses g¹ formed in the hubs of the keys, such that, as either one of the keys is depressed, the shaft G¹¹ will be rocked by the engagement of a shoulder g² presented at one end of the recess with the feather, the other key remaining stationary due to the fact that its associated feather will merely have an idle movement in the recess. As the shaft is rocked by the depression of any one of the shift keys G⁵, G⁶ or G⁷, an arm g³ (see Figs. 4 and 10) pinned at the extreme right end of the shaft will be raised to effect a similar rocking movement of a shaft T¹⁷ journalled in a fixed bracket U of the machine through the medium of an arm T¹⁸ pinned at the left end of said shaft T¹⁷, and which has a nose portion t⁹ at its end overlying the arm g³. As the shaft T¹⁷ is rocked, an arm T¹⁹ pinned near the right end thereof will be raised and, as this arm at its end is pivotally connected to the slide T¹¹, the latter will be raised to effect the

adjustment of the pivoted assembler throat in the manner before described. Upon the release of the keys G⁵, G⁶ or G⁷, the rock shaft T¹⁷ is returned to its normal position, as determined by 5 a banking screw U¹, against which a depending portion T²⁰ of the arm T¹⁹ engages (see Fig. 8), under the influence of a tension spring u fastened at the lower end of said arm and having a fixed anchorage in the bracket U. As the 10 rock shaft T¹⁷ returns to normal position, the rock shaft G¹¹ on which the shift keys are mounted is likewise returned to its normal position by the engagement of the nose portion t⁹ with the underlying arm g³. 15

15 The connection of the consonant key group for the release of the matrices of groups 4 and 8 by the operation of the shift keys G⁴ and G⁸, respectively, will next be described. The depression of these shift keys acts to move the main bank of reeds rearwardly, as before explained. 20 As in the case of the other keys, the parts are restored to normal position when the keys are released.

As shown in Figs. 1 and 7, the main bank of 25 reeds C¹ at the top is guided in a frame V comprising two transverse bars V¹ and V², located one at the front and the other at the rear of the reed bank and connected together at their ends by a pair of arms V³, V⁴ pinned to a rock shaft 30 V⁵, the frame normally holding the reeds in their forward positions through the medium of a tension spring V⁶ connected to a forwardly extending portion of the arm V⁴ at the left, and which has an anchorage in a fixed part of the machine. 35 The arm V⁴ is connected by a long link V⁷ to a second arm V⁸ fixed at the left end of a rock shaft V⁹ journaled at its ends in the side members of the frame H³. Pinned to this rock shaft is a pair of forwardly extending arms V¹⁰, V¹¹, 40 presenting, at their front ends, nose portions overlying the rear end portions of the shift keys G⁴ and G⁸, respectively, the shift key G⁴ being fulcrumed adjacent its center on the pivot bar G⁹, and the shift key G⁸ being fulcrumed on the rock shaft G¹¹. According to this arrangement, 45 should either one of the shift keys G⁴ or G⁸ be depressed, the rock shaft V⁹ will be turned in a clockwise direction, looking at the parts from the right and, through the connections described, will move the upper ends of the reeds rearwardly, 50 thereby connecting certain of the reeds with the bails that operate the reeds of group R, namely, those associated with the auxiliary magazines. When the shift keys G⁴ and G⁸ are released, the 55 bank of the main reeds will be restored to normal position by the tension spring V⁶ acting upon the arm V⁴.

In addition to shifting the main reeds C¹ rearwardly to connect the reeds of group P operated 60 by the consonant key group as well as the fourteen reeds of group Q with the reeds of group R, the shift key G⁸ also effects the adjustment of the pivoted assembler throat B³ associated with the auxiliary magazines from its normal position in operative relation with the upper magazine to its other position in operative relation with the lower magazine. The power mechanism for shifting the pivoted assembler throat A³ associated with the main magazines and the connections between the throat and the power mechanism are duplicated for the auxiliary magazines, and it is thought that no further description is necessary, except to say that the arm B⁵ (see Fig. 3), which is pinned to the shaft B⁴ on which 75 the throat B³ is mounted, is located at the left

end of the shaft B⁴, instead of at the right, so that the rod B⁶ and lever B⁷ for transmitting movement from a cam W, which is a duplicate of the cam T, can be arranged close together to conserve space.

The cam W is operated from the shift key G⁸ through mechanism similar to that for operating the cam T, and which includes a slide W¹ like the slide T¹¹ (see Fig. 8). The connections between the shift key G⁸ and the slide W¹ are 10 slightly different from those which connect the shift keys G⁵, G⁶ and G⁷ with the slide T¹¹, so that these connections will be described in detail. The key G⁸ (see Figs. 4 and 21) is mounted adjacent its center on a sleeve G¹³ rotatably encircling the rock shaft G¹¹ and is fixed to the sleeve by means of a set screw G¹⁴. At the right end of the sleeve G¹³, there is pinned an arm g⁴ extending rearwardly and parallel with the arm g³ and adapted, as the shift key G⁸ is depressed, 15 to effect the rocking of a second sleeve W² rotatably mounted on the rock shaft T¹⁷ (see Fig. 10) through the medium of an arm W³ having a nose portion w overlying the arm g⁴ connected to the first mentioned sleeve. A bail connection W⁴ between the sleeve W² and an arm W⁵ freely journaled at the right end of the rock shaft T¹⁷ transmits the rocking motion of the sleeve W² to the arm, so that the latter, which is connected at its rear end to the slide W¹, will raise the 20 slide, thereby causing the power mechanism to move the pivoted assembler throat B³ from its upper magazine receiving position into its lower magazine receiving position. When the shift key G⁸ is released, the arm W⁵ will be restored 25 to normal position, as determined by a banking screw U², against which a depending portion T²⁰ of the arm engages, by a spring similar to the spring u, the return of the arm W⁵ to normal position not only restoring the shift key G⁸ 30 through the intermediate connections just described, but also causing the downward movement of the slide W¹, which, in a manner similar to the slide T¹¹, causes the power mechanism to return the pivoted assembler throat B³ to its 35 normal position in operative association with the upper magazine.

At this point, it might be stated that, when the reed bank C¹ is shifted rearwardly to connect the twenty-seven reeds of group P, as well as the fourteen reeds of group Q, with the bails C⁵ for operating the reeds of group R, some provision must be made for preventing the operation of the corresponding escapements associated with the main magazines. According to (see Fig. 1), the levers C², actuated by these particular reeds, are formed each with a recess c³, which will permit the upward movement of the associated reeds, when in the rearward position, without affecting the levers. Such recesses, however, are not provided in the remaining levers, since, in some cases, it is desired to actuate the levers in the rearward position of the reeds, as, for instance, in the case of those associated with the channels of the main magazines containing special characters, it being recalled that the special characters in the upper main magazine can be released for composition, even though the consonant key group is connected for the release of matrices in groups 4 and 8 in the 70 auxiliary magazines.

There remains to be described, the various mechanisms for locking against operation, the special character keys which, for any given keyboard condition, will be incapable of releasing 75

their corresponding matrices. For this purpose, three separate locking devices are provided, one for the nine keys controlling the release of the special characters of matrix groups 5, 6 and 1, when the pivoted assembler throat A³ is associated with the upper main magazine as well as for the nine keys controlling the release of the special characters of matrix groups 1, 2 and 3 when the pivoted assembler throat is associated with the lower main magazine. The em key is not locked at any time, since it is operative to release the em space, irrespective of which matrix group is in use. A second locking device is provided for the fourteen keys that control the release of the special characters of matrix groups 4 and 8 in the auxiliary magazines when the consonant key group is connected for releasing the matrices from any one of groups 1, 2, 3, 5, 6 and 7 of the main magazines. The third locking device is subsidiary to the second and locks the seven keys which release the special characters of matrix group 8 when the consonant key group is connected for releasing the matrices of group 4 in the upper auxiliary magazine and also locks the seven keys which release the special characters of group 4 when the consonant key group is connected for releasing the matrices from group 8 in the lower auxiliary magazine.

It will be recalled that the nine reeds for releasing the special characters from groups 1, 2 and 3, and from groups 5, 6 and 7 (i. e., all the special characters of these groups, with the exception of the em space) are each operated from a single slide E, under the control of two rods K (see Figs. 18 and 24). Both rods are operative upon being raised to lift the slide E through the medium of a common bar L, which, unlike the bars controlled by the consonant key group, is plain in its bottom edge, so that the rods K, and consequently the slide E will be operative, irrespective of the position of the shift frame S. One of the rods K, associated with each of the nine slides E, is operated through a bail J¹ and an underlying and overlying lever J and J³, from one of the keys for releasing a special character from the upper main magazine, while the other rod K associated with each slide is operated through similar connections from one of the keys for releasing a special character from the lower main magazine. Thus, while the slides E and the corresponding reeds are always operable, error is avoided by automatically locking one set of keys or another against operation, depending upon which main magazine the pivoted throat A³ is operatively associated with.

This locking device (see Figs. 16 and 17) includes a vertical plate H¹² mounted by means of screw and slot connections H¹³, against the rear side of the keyboard frame and formed with a number of apertures H¹⁴ arranged to cooperate with the rear ends of the fore-and-aft levers J which actuate the keyboard bails J¹ and are themselves actuated directly by the finger keys in question. As shown in Fig. 16, the slots H¹⁴ are eighteen in number, the nine at the left being utilized in the locking of the keys that release the special characters from the lower main magazine, and the nine at the right being utilized in the locking of the keys for releasing the special characters from the upper main magazine. The plate is arranged for limited movement in an up and down direction and, in its upper position (see Fig. 17), the levers J associated with the keys for releasing the special characters from the lower magazine (those of the type at the top)

are locked against movement by the coaction of an inclined portion J⁵ formed at the rear end of said levers and a bevelled shoulder H¹⁵ located just beneath the associated slot. The levers J that are active in releasing the special characters from the upper main magazine (those of the type at the bottom) are formed at their rear ends with vertical portions J⁶ and, when the plate is in its uppermost position, these vertical portions register with the slots H¹⁴, so that these levers are free to move as the corresponding keys of the keyboard are operated. When the plate H¹² is in its lowermost position, as indicated by the dotted lines in Fig. 17, the vertical portions J⁶ of the levers J that are active in releasing the special characters from the main magazine, bank against the plate H¹², thereby locking these levers, as well as the corresponding finger keys, against movement. On the other hand, in this position of the plate H¹², the slots H¹⁴ associated with the levers active in releasing the special characters from the lower main magazine are in register with the ends of said levers, so as to permit the latter to be moved about their respective pivots, the bevelled shoulders H¹⁵, under such conditions, being below and spaced from the levers where they will not interfere.

The locking plate H¹² is moved to its different positions of adjustment under the control of the pivoted assembler throat A³, the connections for this purpose including a pair of short fingers H¹⁶, which engage corresponding apertures H¹⁷ formed in the plate near the upper edge thereof, and which are mounted on a long transverse rock shaft H¹⁸ journaled in the keyboard frame and actuated from the pivoted assembler throat through the medium of a long link H¹⁹ (see Fig. 1) connected between a pair of crank arms H²⁰, A¹², one pinned to the rock shaft H¹⁸, and the other to the rock shaft A⁴ on which the assembler throat is mounted. According to this arrangement, when the pivoted assembler throat A³ is operatively associated with the upper magazine, the locking plate H¹² will be located in its upper position of adjustment, wherein the keys for controlling the release of the special characters in the lower main magazine will be locked against movement; whereas, when the pivoted assembler throat is turned to the position wherein it is associated with the lower magazine, the locking plate will be located in its lower position of adjustment, wherein the keys for releasing the special characters from the upper main magazine are locked, all as previously described.

The locking device for the fourteen keys which release the special characters from the auxiliary magazines, as well as the subsidiary locking devices for these keys, are best illustrated in Figs. 6, 7, 12, 19 and 20. The main locking device includes a horizontal slide bar H²¹ mounted at the rear of the keyboard and provided with lugs or protuberances H²² adapted to engage corresponding notches e formed in the lower end portions of the fourteen vertical slides E (Figs. 6 and 12), it being noted that these slides are shaped somewhat differently in their lower ends from the other slides E, i. e., they have forwardly extending portions e¹ in which the notches e are located. Normally, the horizontal slide bar H²¹ is held toward the right, looking at the machine from the back (see Fig. 6), by a compression spring H²³ reacting between a shoulder H²⁴ formed on a bar H²⁵ fixed to the slide and a fixed part of the keyboard frame. In this position of the slide, the protuberances H²² engage in the

notches e in the slides E , so as to prevent the latter from being actuated by their associated keys.

The fourteen slides in question are those which actuate fourteen of the reeds in group Q. Consequently, they must be released for operation not only when the consonant key group is connected for the release of the matrices of groups 4 and 8 in the auxiliary magazines so that the special characters in these groups can be released at the same time, but also when the consonant key group is connected for the release of the matrices in groups 3 and 7, since these slides are also used for the release of the regular characters in these latter groups. Accordingly, provision is made for actuating the horizontal slide H^{21} to its inactive position upon the operation of any one of the shift keys G^3 , G^4 , G^7 or G^8 , which are the keys for connecting the consonant key group with the matrix groups 3, 4, 7, and 8, respectively.

It will be recalled that when either one of the shift keys G^4 or G^8 is depressed, these keys (see Fig. 7) through the levers V^{10} and V^{11} , rotate a rock shaft V^9 which, through a lever V^8 connected at the end of the rock shaft and a link V^7 , move the frame V which shifts the reeds C^1 associated with the main magazines rearwardly into engagement with balls C^6 , whereby the reeds of group R (those for releasing the matrices of groups 4 and 8) may be operated. The lever V^8 (see Figs. 19 and 20) is provided with an upwardly extending arm v which, at its upper end, is connected by means of a pin and slot connection to one end of a link v^1 . The link v^1 at its other end is connected to one arm of a bell crank lever H^{26} , pivotally mounted on the keyboard frame and which has a second arm overlying the horizontal arm of a second lever H^{27} , which latter is likewise pivotally mounted on the keyboard frame and has a depending arm connected at the end of the rod H^{25} associated with the horizontal slide bar H^{21} . The arrangement is such that, as either one of the shift keys G^4 or G^8 is depressed, the lever V^8 is turned in a counterclockwise direction, looking at the machine from the left and, in doing so, will, through the link connection, cause the lever H^{26} to press down on the underlying lever H^{27} , with the result that the horizontal slide bar is moved to the left in Fig. 6, in which position the protuberances H^{22} are out of engagement with the notches e in the fourteen slides E . Upon the release of the shift keys G^4 and G^8 , the parts, including the horizontal slide H^{21} , the lever H^{26} and the link v^1 , are restored to their normal positions by the action of the spring H^{23} associated with the slide, thus relocking the slides E .

The horizontal slide H^{21} is similarly moved to release the fourteen slides upon the depression of the shift keys G^3 and G^7 . It will be recalled that, upon the depression of these keys, the shift frame S is moved rearwardly. As this movement of the shift frame takes place, a shoe s^{10} , fastened on the left arm S^1 of the shift frame, engages an upwardly projecting lug v^2 on the link v^1 , so as to move the link, and consequently the lever H^{26} , in the same way as when these parts were actuated by the shift keys G^4 and G^8 . The result is that the horizontal slide bar H^{21} is moved to free the slides E as before and, upon the release of the shift keys G^3 and G^7 , the restoration of the shift frame S to normal position permits said horizontal bar likewise to be returned to normal position, wherein it again locks the slides.

While the fourteen slides E are free to operate

(insofar as the horizontal slide bar H^{21} is concerned), when any of the shift keys G^3 , G^4 , G^7 and G^8 are depressed, the subsidiary locking device, previously mentioned, will be effective to lock seven of the slides when the shift key G^4 is depressed, and the other seven slides when the shift key G^8 is depressed. In other words, when the shift key G^4 is depressed, the subsidiary locking device will lock the seven keys Nos. 54 to 60, which control the release of the special characters from matrix group 8 in the lower auxiliary magazine; whereas, when the shift key G^8 is depressed, the subsidiary locking device will be active to lock the seven keys Nos. 38 to 44, which control the release of the special characters of matrix group 4 in the upper auxiliary magazine. These locking devices (see Figs. 7 and 25) consist each of a short horizontal bar v^3 , v^4 sufficiently wide to embrace seven slides E and arranged to engage shoulders e^2 in the front edges of the slides near the upper ends thereof. The bar v^4 at the right is connected through side members v^5 and a collar v^6 rigidly to a rock shaft v^7 , which is actuated through an arm v^8 pinned to the shaft and a link v^9 connected to the arm and the key lever G^4 . The other bar v^3 at the left is connected by side members v^{10} to a sleeve v^{11} freely mounted on the rock shaft v^7 , and which is rigidly connected to another sleeve v^{12} , likewise freely mounted on the rock shaft v^7 by a bail v^{13} , the sleeve v^{12} at the right having a forwardly extending arm v^{14} connected through a link v^{15} to the key lever G^8 . The arrangement is such that, as the key lever G^4 is depressed, the rock shaft v^7 is turned to project the bar v^4 at the right over the shoulders e^2 of the seven associated slides (i. e., those active in releasing the special characters from the lower auxiliary magazine), thereby preventing the upward movement of the slides; and likewise, when the shift key G^8 is depressed, the bar v^3 at the left, through the medium of the sleeves v^{11} , v^{12} and the link connection v^{15} with the key lever, will be rocked rearwardly to engage over the shoulders e^2 on the seven slides at the left (i. e., those which are active in the release of the special characters from the upper auxiliary magazine) to prevent these slides from being operated. Since the connections between the bars v^3 , v^4 and the shift keys G^4 and G^8 are positive, the affected slides E will be released when the shift keys return to normal position.

Since the locking slide bar H^{21} acts upon slides E and not upon the keys, the special keys for releasing the special characters of matrix groups 4 and 8 will be depressible when the corresponding slides are freed by the operation of shift keys G^3 and G^7 , but the depression of the keys at such times will have no effect, since, it will be recalled, when the shift frame S is in its rearward position, the upward movement of the rods K, controlled by such keys, is an idle one, due to the character of the tooth and notch combination in the bars L associated with such rods. Similar conditions hold true when the shift frame S is moved to its forward position, upon the depression of shift keys G^1 and G^5 , although, as a matter of fact, under these conditions, the slides E , controlled by the special keys of matrix groups 4 and 8, could not be actuated in any event, since the horizontal slide bar H^{21} is maintained in its active slide locking position.

It is obvious from the foregoing that the present invention greatly facilitates machine composition in the Hebrew language, in that, only one key is necessary for each consonant char-

acter (those of the consonant key group) and only one key for each of the vowels. Furthermore, it permits the use of a relatively large number of special characters, punctuation marks, etc., without an excessive number of keys, there being in the embodiment illustrated sixty keys in all (twenty-seven regular and thirty-three special).

While it is thought the operation of the improved machine will be clear from the foregoing description, a brief recapitulation of the various characters available under the different settings or "shifts" might not be amiss. Thus, it will be recalled (see Figs. 25, 26) that in the normal setting of the machine, the consonant key group is connected for the release of the matrices bearing the regular characters of group 2. In other words, these matrices can be released solely by the operation of the twenty-seven keys of the keyboard that are common to all the groups, no recourse to a shift key being necessary. The characters available in this group are shown in Fig. 26 under the caption "Group 2". To the left of the caption is found the notation "No shift—37 characters", indicating that for this group, the shift frame remains in its normal position and that thirty-seven characters are available. These thirty-seven characters include the twenty-seven regular consonant characters, the three special characters in channels Nos. 7, 12 and 25 of this group, and seven special characters (grouped apart at the right), three in the three last channels of group 1, and four in the four last channels of group 3.

When, during the course of composition, it becomes necessary to use the vowel characteristic of group 1 in association with a regular consonant character, the operator depresses the shift key indicated by such vowel, i. e., the shift key G¹ and, while holding the key depressed, operates the keys of the consonant key group corresponding to those characters which are to be composed in association with the vowel. The characters available for composition when this key is active, are in the group captioned "Group 1" (see Fig. 26). To the left of the caption is the notation "Forward shift—37 characters", indicating that for this group, the shift frame is moved forward to effect the proper keyboard connections and that thirty-seven characters are available, namely, the twenty-seven regular characters of group 1 and the three special characters stored in the three rightmost channels of this group, as well as seven special characters (those grouped apart at the right), three being stored in channels Nos. 7, 12 and 25 of group 2, and four in the four rightmost channels of group 3.

Should the operator desire to compose a regular character in association with the vowel characteristic of group 3, he depresses the shift key indicated by this vowel, i. e., the shift key G³ and, while holding the key depressed, operates the keys of the consonant key group corresponding to those characters which are to be composed in association with such vowel. The characters available for composition when this key is active are in the group captioned "Group 3" (see Fig. 26). To the left of the caption is the notation "Backward shift—37 characters", indicating that for this group, the shift frame is moved backward to effect the proper keyboard connections, and that thirty-seven characters are available, namely, the twenty-seven regular characters of group 3 and the four special characters located in the four rightmost channels of this group, as well as six special characters (those grouped apart at

the right), three being stored in the three rightmost channels of group 1, and three in channels Nos. 7, 12 and 25 of group 2.

Similarly, should the operator desire to compose a regular character in association with the vowel characteristic of group 4, the shift key indicated by this vowel, i. e., the key G⁴, is depressed and those keys of the consonant key group actuated corresponding to the characters desired to be composed in association with such vowel. The characters available for composition when this key is active are shown in Fig. 26 under the caption "Group 4". At the left of the caption is the notation "No shift—reeds only—44 characters", indicating that for this group, the shift frame remains in its normal position, the proper keyboard connections being effected only by the rearward displacement of the main group of reeds to connect with a bail box unit through which selected main reeds can actuate the reeds associated with the auxiliary magazines. The notation further indicates that for this condition of the keyboard, forty-four characters are available, namely, the twenty-seven regular characters of group 4 and the seven special characters stored in the seven rightmost channels of this group, as well as ten special characters (those grouped apart at the right), stored three in the three rightmost channels of group 1, four in the four rightmost channels of group 3, and three in channels Nos. 7, 12 and 25 of group 2.

Regular characters in association with the vowel characteristic of group 5 may be composed by depressing the shift key indicated by this vowel, i. e., the shift key G⁵ and, while the key is depressed, composing the desired characters by actuating the appropriate keys of the consonant key group. The characters available under this keyboard connection are shown in Fig. 26 under the caption "Group 5", at the left of which is the notation "Forward shift—main throat—37 characters", indicating that the proper keyboard connections are effected in this instance by a forward movement of the shift frame coupled with a pivotal movement of the assembler throat A³ from its normal position, wherein it completes an operative connection between the upper magazine in operative position and the assembler entrance A¹ to a position wherein it completes an operative connection between the lower magazine in operative position and the assembler entrance. The notation further indicates that for this condition of the keyboard, thirty-seven characters are available, namely, the twenty-seven regular characters of group 5 and the three special characters stored in the three leftmost channels thereof, as well as seven special characters (those grouped apart at the right), stored three in the three channels, Nos. 7, 12 and 25 of group 6, and four in the four rightmost channels of group 7.

Regular characters in association with the vowel characteristic of group 6 may be composed by depressing the shift key indicated by this vowel, i. e., the shift key G⁶ and, while the key is depressed, actuating the appropriate keys of the consonant key group. The characters available under this keyboard connection are shown in Fig. 26 under the caption "Group 6", at the left of which is the notation "No shift—main throat—37 characters", indicating that the proper keyboard connections are effected here by maintaining the shift frame in its normal position, and shifting the assembler throat A³ into cooperative relation with the lower magazine in operative position. The thirty-seven characters, in

dicated as available, are the twenty-seven regular characters of group 6 and the three special characters stored in channels, Nos. 7, 12 and 25 thereof, as well as seven special characters (those grouped apart at the right), stored three in the three leftmost channels of group 5, and four in the four rightmost channels of group 7.

Regular characters in association with the vowel characteristic of group 7 may be composed by depressing the shift key indicated by this vowel, i. e., the shift key G⁷, and actuating the appropriate keys of the consonant key group. The characters available under this keyboard connection are shown in Fig. 26 under the caption "Group 7", at the left of which is the notation "Backward shift—main throat—37 characters", indicating that the proper keyboard connections are effected by a backward shift of the shift frame and a shifting of the main throat similar to that effected when groups 5 and 6 are rendered operative. The thirty-seven characters indicated as available are the twenty-seven regular characters of group 7 and the four special characters stored in the four rightmost channels thereof, as well as six special characters (those grouped apart at the right), stored three in the three leftmost channels of group 5, and three in channels, Nos. 7, 12 and 25 of group 6.

Regular characters in association with the vowel characteristic of group 8 may be composed by depressing the shift key indicated by this vowel, i. e., the shift key G⁸ and, while the key is depressed, actuating the appropriate finger keys of the consonant key group. The characters available for this setting are shown in Fig. 26 under the caption "Group 8", at the left of which is the notation "No shift—auxiliary throat and reeds—44 characters", indicating that the proper keyboard connections are effected by maintaining the shift frame in its normal position, and shifting the auxiliary throat from its normal position, wherein it completes an operative connection between the upper auxiliary magazine and the assembler entrance to a position wherein it completes an operative connection between the lower auxiliary magazine and the assembler entrance, and also that the main group of reeds is moved rearwardly to connect with the bail box unit, through which selected main reeds can actuate the reeds associated with the auxiliary magazines. The forty-four characters available are the twenty-seven regular characters of group 8, and the seven special characters located in the seven rightmost channels thereof, as well as the ten special characters (grouped apart at the right) of groups 1, 2 and 3.

In the embodiment of the invention illustrated, the number of characters available is the minimum which can be had with the instant magazine arrangement. Actually the number of characters could be doubled by placing two on each matrix, one above the other, and using the well known duplex rail in the assembler elevator. If a duplex rail were used, the shift keys could be duplicated, the duplicate shift keys being arranged to operate said rail, as well as the respective connections herein set forth. Alternatively, a single shift key could be utilized for operating the duplex rail and two index characters placed on each shift key, one for indicating the characters normally available and the other for indicating the characters available when the duplex rail is used.

It is also contemplated that the number of characters available could be quadrupled merely

by placing four characters on each matrix, two at one edge and two at the other. Such an arrangement, of course, would involve the use of a duplex rail in the assembler, as well as means for reversing the matrices during assembly.

In the accompanying drawings, the invention has been shown merely by way of example and in preferred form, and obviously, many variations and modifications may be made therein which will still be comprised within its spirit. It is to be understood, therefore, that the invention is not limited to any specific form or embodiment, except insofar as such limitations are specified in the appended claims.

It will also be understood that the invention is not confined to Hebrew, as there are other languages to which it may be applied, like Arabic, Syriac, Turkish, Devanāgari and others which resemble Hebrew as regards the use of vowels in conjunction with consonants. In this connection, it may also be explained that the word "vowel" or "vowels" as used throughout the specification and in the claims is employed in its broadest sense, being intended to comprehend any symbol which, when associated with a consonant, has the effect of modifying the consonant in sound or significance.

It should also be understood that the invention in its purely mechanical phases could be used to advantage in any case where it is desired to employ a limited number of finger keys in conjunction with a much greater number of characters, it being obvious that if the matrices are properly stored in groups according to the arrangement described, the keyboard may be operatively connected to any selected one of the groups by the actuation of the appropriate shift keys.

Having thus described my invention, what I claim is:

1. A typographical composing machine comprising, in combination, a font of typographical elements divided into a plurality of groups, the elements of one group bearing consonants without vowels and those of the remaining groups bearing the same consonants with vowels, the vowels being the same in the individual groups but differing as between the groups, a channeled magazine arrangement wherein the typographical elements are stored according to group, a keyboard comprising a group of finger keys common to all the element groups, and means whereby said group of finger keys may be operatively connected to the magazine channels containing any selected one of the element groups.

2. A typographical composing machine comprising, in combination, a font of typographical elements divided into a plurality of groups, the elements of one group bearing consonants without vowels and those of the remaining groups bearing the same consonants with vowels, the vowels being the same in the individual groups but differing as between the groups, a channeled magazine arrangement wherein the typographical elements are stored according to group, a keyboard comprising a group of finger keys common to all the element groups and bearing index characters representing the consonants repeated throughout the groups, and shift keys for connecting said group of finger keys to the magazine channels containing any selected one of the vowel-carrying element groups, said shift keys bearing index characters representing the vowels differentiating said groups.

3. A typographical composing machine com-

prising, in combination, a font of typographical elements divided into a plurality of groups, the elements of one group bearing consonants without vowels and those of the remaining groups bearing the same consonants with vowels, the vowels being the same in the individual groups but differing as between the groups, a channeled magazine arrangement wherein the typographical elements are stored according to group, a keyboard comprising a group of finger keys common to all the element groups and bearing index characters representing the consonants repeated throughout the groups, said finger keys being normally connected to the magazine channels containing the non-vowel-carrying element group, and shift keys for connecting said group of finger keys to any selected one of the vowel-carrying element groups, said shift keys bearing index characters representing the vowels differentiating said groups.

4. A typographical composing machine comprising, in combination, a font of typographical elements divided into a plurality of groups, the elements of one group bearing consonants without vowels and those of the remaining groups bearing the same consonants with vowels, the vowels being the same in the individual groups but differing as between the groups, a channeled magazine arrangement wherein the typographical elements are stored according to group, a keyboard comprising a group of finger keys common to all the element groups and bearing index characters representing the consonants repeated throughout the groups, said finger keys being normally connected to the magazine channels containing the non-vowel-carrying element group, shift keys for connecting said group of finger keys to any selected one of the vowel-carrying element groups, said shift keys bearing index characters representing the vowels differentiating said groups, and means operable automatically upon the release of any shift key for restoring the normal connection of the group of finger keys to the magazine channels containing the non-vowel-carrying element group.

5. A typographical composing machine according to claim 3, wherein the channeled magazine arrangement comprises a main magazine containing a plurality of the element groups, one of which is the non-vowel-carrying element group, and wherein certain of the shift keys are operative to connect the group of finger keys to the magazine channels containing one or another of the vowel-carrying element groups stored in said magazine.

6. A typographical composing machine according to claim 3, wherein the channeled magazine arrangement comprises a main magazine containing a plurality of the element groups, one of which is the non-vowel-carrying element group, and an auxiliary magazine containing another of the element groups, and wherein certain of the shift keys are operative to connect the group of finger keys to the magazine channels containing one or another of the vowel-carrying element groups stored in said main and auxiliary magazines.

7. A typographical composing machine according to claim 3, wherein the channeled magazine arrangement comprises two main magazines each containing a plurality of the element groups, one of which is the non-vowel-carrying element group, and wherein certain of the shift keys are operative to connect the group of finger keys to the magazine channels containing one or another

of the vowel-carrying element groups stored in said main magazines.

8. A typographical composing machine according to claim 3, wherein the channeled magazine arrangement comprises two main magazines, each containing a plurality of the element groups, one of which is the non-vowel-carrying element group, and two auxiliary magazines each containing another of the element groups, and wherein the shift keys are operative to connect the group of finger keys to the magazine channels containing one or another of the vowel-carrying element groups stored in said main and auxiliary magazines.

9. A typographical composing machine according to claim 3, wherein the channeled magazine arrangement comprises a main magazine containing three of the element groups, one of which is the non-vowel-carrying element group, and wherein certain of the shift keys are operative to connect the group of finger keys to the magazine channels containing one or another of the vowel-carrying element groups stored in said magazine, characterized in this that the typographical elements are released from the magazine channels by a series of power-operated main reeds divided into three groups, one for each of the element groups, and that intermediate mechanical devices, controlled by the aforementioned shift keys, are adjustable to connect the group of finger keys to one or the other set of reeds serving the vowel-carrying element groups.

10. A keyboard for a typographical composing machine equipped with a font of typographical elements divided into a plurality of groups, the elements of one group bearing consonants without vowels and those of the remaining groups bearing the same consonants with vowels, the vowels being the same in the individual groups but differing as between the groups, said keyboard comprising a group of finger keys common to all the element groups and bearing index characters representing the consonants repeated throughout the groups, and a plurality of shift keys bearing index characters representing the vowels differentiating said groups.

11. A typographical composing machine comprising, in combination, a main magazine presenting a plurality of groups of channels, an auxiliary magazine arranged alongside the main magazine and presenting another group of channels, a keyboard having a group of finger keys common to all of said channel groups, and means whereby said group of finger keys may be connected to any selected one of said channel groups.

12. A typographical composing machine comprising, in combination, a main magazine presenting a plurality of groups of channels, an auxiliary magazine arranged alongside the main magazine and presenting another group of channels, a keyboard having a group of finger keys common to all of said channel groups and normally connected to a given one thereof, and shift keys, one for each of the other channel groups, operable to connect said finger key group to any selected one thereof.

13. A typographical composing machine comprising, in combination, two superposed main magazines each presenting a plurality of groups of channels, a keyboard having a group of finger keys common to all of said channel groups, and shift keys whereby said group of finger keys may be connected to different selected ones of said channel groups, said shift keys each being operable to connect the finger key group to the corre-

sponding channel group irrespective of its magazine location.

14. A typographical composing machine comprising, in combination, two superposed main magazines each presenting a plurality of groups of channels, a keyboard having a group of finger keys common to all of said channel groups, and normally connected to a given one thereof, and shift keys, one for each of the other channel groups, operable to connect said finger key group to any selected one thereof irrespective of its magazine location.

15. A typographical composing machine comprising, in combination, two superposed main magazines each presenting a plurality of groups of channels, two superposed auxiliary magazines arranged alongside the main magazines and each presenting another group of channels, a keyboard having a group of finger keys common to all of said channel groups, and shift keys whereby said group of finger keys may be connected to different selected ones of said channel groups, said shift keys each being operable to connect the finger key group to the corresponding channel group irrespective of its magazine location.

16. A typographical composing machine comprising, in combination, two superposed main magazines each presenting a plurality of groups of channels, two superposed auxiliary magazines arranged alongside the main magazines and each presenting another group of channels, a keyboard having a group of finger keys common to all of said channel groups and normally connected to a given one thereof, and shift keys, one for each of the other channel groups, operable to connect said finger key group to any selected one thereof.

17. A typographical composing machine comprising, in combination, a main magazine provided with escapements, an auxiliary magazine arranged alongside the main magazine and also provided with escapements, a series of actuating reeds for the escapements of the main magazine divided into a plurality of groups, another group of actuating reeds for the escapements of the auxiliary magazine, a keyboard having a group of finger keys common to all of said reed groups, and means whereby said group of finger keys may be connected to any selected one of said reed groups.

18. A typographical composing machine comprising, in combination, a main magazine provided with escapements, an auxiliary magazine arranged alongside the main magazine and also provided with escapements, a series of actuating reeds for the escapements of the main magazine divided into a plurality of groups, another group of actuating reeds for the escapements of the auxiliary magazine, a keyboard having a group of finger keys common to all of said reed groups, and normally connected to a given group of reeds for the main magazine, and shift keys, one for each of the other reed groups, operable to connect said finger key group to any selected one thereof.

19. A typographical composing machine according to claim 18, wherein the connection of the finger key group to the reed group for the auxiliary magazine is effected through the given group of reeds for the main magazine to which the finger key group is normally connected.

20. A typographical composing machine comprising, in combination, two main magazines each presenting a plurality of groups of channels with escapements, a common series of actuating reeds

for the escapements of said magazines divided into a like plurality of groups, a keyboard having a group of finger keys common to all of said channel groups, means whereby said group of finger keys may be connected to any selected one of the reed groups, and means whereby said selected reed group may be connected to the corresponding escapements of one magazine or the other as required.

21. A typographical composing machine comprising, in combination, two main magazines each presenting a plurality of groups of channels with escapements, a common series of actuating reeds for the escapements of said magazines divided into a like plurality of groups, a keyboard having a group of finger keys common to all of said channel groups and normally connected to a given group of reeds, and shift keys, one for each of the channel groups less one, operable to connect the finger key group to a different group of reeds or to connect the reeds as a whole to the escapements of one magazine or the other, or to effect both such connections, according to the shift key operated.

22. A typographical composing machine comprising, in combination, two main magazines each presenting a plurality of groups of channels with escapements, a common series of actuating reeds for the escapements of said magazines divided into a like plurality of groups, two auxiliary magazines arranged alongside the main magazines and each presenting another group of channels with escapements, another and common group of actuating reeds for the escapements of the auxiliary magazines, a keyboard having a group of finger keys common to all of said channel groups, means whereby said group of finger keys may be connected to any selected one of the reed groups, and means whereby said selected actuating reed group may be connected to the corresponding escapements of one or the other of the magazines to which it is common.

23. A typographical composing machine comprising, in combination, two main magazines each presenting a plurality of groups of channels with escapements, a common series of actuating reeds for the escapements of said magazines divided into a like plurality of groups, two auxiliary magazines arranged alongside the main magazines and each presenting another group of channels with escapements, another and common group of actuating reeds for the escapements of the auxiliary magazines, a keyboard having a group of finger keys common to all of said channel groups, and normally connected to a given group of reeds for the main magazines, and shift keys, one for each of the channel groups less one, operable to connect said finger key group to one or another of the other reed groups or to connect said selected actuating reed group to the corresponding escapements of one or the other of the magazines to which it is common, or both, according to the shift key operated.

24. A typographical composing machine according to claim 21, wherein the actuating reeds are normally connected to the escapements of a given one of the magazines, and including means for restoring said normal connection upon the release of any shift key which temporarily breaks said connection.

25. A typographical composing machine according to claim 23, wherein the actuating reeds for both the main and auxiliary magazines are normally connected to the escapements of given ones of their respective magazines, and includ-

ing means for restoring said normal connection upon the release of any shift key which temporarily breaks said connection.

26. A typographical composing machine comprising, in combination, a channeled magazine arrangement comprising two main magazines containing each a corresponding plurality of channel groups, a key board comprising a group of finger keys common to all of said channel groups, a series of power-operated reeds normally connected to the channels of one of the magazines and divided into a plurality of groups corresponding in number to the number of channel groups in each magazine and to one of which 10 reed groups the group of finger keys is normally connected, intermediate mechanical devices adjustable to connect the group of finger keys to a different group of reeds and to connect the series of reeds to the channels of the other magazine, and shift keys operable to control the intermediate mechanical devices selectively, whereby the group of finger keys can be rendered operative to effect the release of typographical elements from any desired group of magazine channels.

27. A typographical composing machine comprising, in combination, a channeled magazine arrangement comprising two main magazines containing each a corresponding plurality of 30 channel groups and an auxiliary magazine containing another channel group, a keyboard comprising a group of finger keys common to all of said channel groups, a series of power-operated main reeds normally connected to the channels of one of the main magazines and divided into a plurality of groups corresponding in number to the number of channel groups in each main magazine, a series of auxiliary reeds, intermediate mechanical devices adjustable to connect the group of finger keys to a different group of main reeds and to connect the whole series of main reeds to the channels of the other main magazine and to connect the auxiliary reeds to certain 40 of the main reeds, and shift keys operable to control the intermediate mechanical devices selectively, whereby the group of finger keys can be rendered operative to effect the release of typographical elements from any desired group of magazine channels.

50. 28. A typographical composing machine comprising, in combination, a channeled magazine arrangement comprising two main magazines containing each a corresponding plurality of channel groups, and two auxiliary magazines containing each another channel group, a keyboard comprising a group of finger keys common to all of said channel groups, a series of power-operated main reeds normally connected to the channels of one of the main magazines and divided into a plurality of groups corresponding in number to the number of element groups in each main magazine, a series of auxiliary reeds normally connected to the channels of one of the auxiliary magazines, intermediate mechanical devices adjustable to connect the group of finger keys to a different group of main reeds and to connect the series of main reeds to the channels of the other main magazine and to connect the auxiliary reeds to certain of the main reeds and to connect the series of auxiliary reeds to the channels of the other auxiliary magazine, and shift keys operable to control the intermediate mechanical devices selectively whereby the group of finger keys can be rendered operative to effect the release of typographical elements from any desired group of magazine channels.

graphical elements from any desired group of magazine channels.

29. A typographical composing machine including, in combination, a pair of superposed magazines, an assembler entrance having a relatively fixed portion and a movable portion adjustable to complete an operative connection between the fixed portion and either one of the magazines, power-operated devices for moving the adjustable portion of the assembler entrance, a key for controlling the operation of said devices, and means acting, as the key is operated, to effect movement of the adjustable portion of the assembler entrance from a position in operative relation with one magazine to a position in operative relation with the other magazine and, as the key is released, to restore said adjustable portion of the assembler entrance to its original position.

30. A typographical composing machine including, in combination, a pair of superposed magazines, an assembler entrance having a relatively fixed portion and a movable portion adjustable to complete an operative connection between the fixed portion and either one of the magazines, power-operated devices for moving the adjustable portion of the assembler entrance, a key for controlling the operation of said devices, cam means for operating said devices, and mechanism for rendering the cam means active, once as the key is operated to effect movement of the adjustable portion of the assembler entrance from a position in operative relation with one magazine to a position in operative relation with the other magazine, and again as the key is released to restore said adjustable portion of the assembler entrance to its original position.

31. A typographical composing machine including, in combination, a pair of superposed magazines, an assembler entrance having a relatively fixed portion and a movable portion adjustable to complete an operative connection between the fixed portion and either one of the magazines, power-operated devices for moving the adjustable portion of the assembler entrance, a key for controlling the operation of said devices, cam means for operating said devices, and mechanism including a trip dog for rendering the cam means active, said key being adapted upon operation to trip the dog, thereby to effect movement of the adjustable portion of the assembler entrance from a position in operative relation with one magazine to a position in operative relation with the other magazine, and upon being released again to trip the dog, thereby to restore said adjustable portion of the assembler entrance to its original position.

32. A typographical composing machine including, in combination, a plurality of superposed channeled matrix magazines, a series of reeds for releasing the matrices from said magazines and adapted under certain conditions to be connected with the channels of one magazine and under other conditions with the channels of the other magazine, and a keyboard including one series of keys cooperating with the reeds when the latter are connected with channels of one magazine and a second series of keys cooperating with the same reeds when the latter are connected with channels of the other magazine.

33. A typographical composing machine including, in combination, a plurality of superposed channeled matrix magazines, a series of reeds for releasing the matrices from said magazines and adapted under certain conditions to be connected with the channels of one magazine and

under other conditions with the channels of the other magazine, a keyboard including one series of keys cooperating with the reeds when the latter are connected with channels of one magazine and a second series of keys cooperating with the same reeds when the latter are connected with channels of the other magazine, and mechanism for locking the first series of keys when the second series is connected for operating the reeds.

10 and for locking the second series of keys when the first series is connected for operating the reeds.

34. A typographical composing machine including, in combination, a pair of superposed channeled matrix magazines, an assembler entrance having a relatively fixed portion and a movable portion adjustable to complete an operative connection between the fixed portion and either one of the magazines, a series of reeds for releasing the matrices from one or the other of said magazines depending upon the adjustment of the assembler entrance, a keyboard including one series of keys cooperating with the reeds in one adjustment of the assembler entrance and a second series of keys cooperating with the same reeds in another adjustment of the assembler entrance, and mechanism controlled automatically according to the adjustment of the assembler entrance for locking one or the other of the series of keys.

35. A typographical composing machine including, in combination, a font of typographical elements, a channeled magazine arrangement wherein said elements are stored, a series of escapement actuating reeds, at least some of which under certain conditions are adapted to release the typographical elements from one set of magazine channels and under other conditions to release the typographical elements from a different set of magazine channels, a keyboard including a plurality of sets of finger keys corresponding to said sets of magazine channels and operable to release the typographical elements therefrom through a common set of reeds, and means rendering each set of finger keys inoperative to operate the common set of reeds when the other set of finger keys is operatively connected therewith.

36. A combination according to claim 35, wherein the common set of reeds is connected for the release of typographical elements from the different sets of channels under the control of shift keys which also control the means for rendering one or the other sets of finger keys inoperative.

37. A typographical composing machine including, in combination, a font of typographical elements divided into a plurality of groups, a channeled magazine arrangement wherein the typographical elements are stored according to

group, a series of power-operated escapement actuating reeds divided into a plurality of groups and normally connected for the release of typographical elements from some of said groups of typographical elements, a keyboard comprising a series of finger keys common to all of said element groups, and means including a single control element for simultaneously shifting the control of the group of finger keys from one group of reeds to another and for connecting the reeds for the release of typographical elements from other of said groups of typographical elements.

38. A typographical composing machine comprising, in combination, a main magazine provided with escapements, an auxiliary magazine arranged alongside the main magazine and also provided with escapements, a main series of actuating reeds for the escapements of the main magazine, an auxiliary series of actuating reeds for the escapements of the auxiliary magazine, motion transmitting devices for connecting the auxiliary reeds to a corresponding number of main reeds, means for moving the main reeds as a whole from their normal position to make such connection with the motion transmitting devices and to break the connection of the corresponding reeds with the escapements of the main magazine, and means whereby the remainder of the main reeds maintain their connection with the escapements of the main magazine in either position of the main series of reeds.

39. A typographical composing machine comprising, in combination, a magazine arrangement presenting two groups of channels, a keyboard having a group of finger keys common to both of said channel groups, power mechanism operable in successive cycles to connect said group of finger keys to first one and then the other group of magazine channels, and a control element for said power mechanism acting at each operation to effect a dual operation of the power mechanism, whereby the finger key group is normally connected to a given one of the channel groups.

40. A typographical composing machine comprising, in combination, a magazine arrangement presenting two groups of channels, a keyboard having a group of finger keys common to both of said channel groups and normally connected to a given one thereof, power mechanism operable in successive cycles to connect said group of finger keys to the other group of magazine channels and then to restore its normal connection to the first mentioned group of magazine channels, and a depressible finger key controlling said power mechanism, said finger key acting as it is depressed to inaugurate the first cycle of operation of the power mechanism and as it is released to inaugurate the second cycle of operation thereof.

LUTHER E. MORRISON.
